UNITED STATES PATENT OFFICE

101,479

DESIGN FOR A COMBINATION LAMP AND FAN

William L. Kisling, St. Louis, Mo.

Application June 1, 1936, Serial No. 62,940

Term of patent 14 years

To all whom it may concern:

Be it known that I, William L. Kisling, a citizen of the United States, residing at St. Louis, State of Missouri, have invented a new, original, and ornamental Design for a Combination Lamp and Fan, of which the following is a specification, reference being had to the accompanying drawing, forming part thereof.

In the drawing:

Figure 1 is a side elevation of a combination lamp and fan constituting the design.

Figure 2 is an inverted plan view thereof.

I claim:

The ornamental design for a combination lamp and fan, as shown.

WILLIAM L. KISLING.
